Primary Examiner — Sheryl Lane*Assistant Examiner* — Catherine Posthauer(74) *Attorney, Agent, or Firm* — Chun-Ming Shih; HDLS IPR Services(57) **CLAIM**

The ornamental design for an inner packing element of box, as shown and described.

DESCRIPTION

FIG. 1 is a perspective view of an inner packing element of box showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and
FIG. 8 is second perspective view showing the inner packing element of box; and,
FIG. 9 is a perspective view showing the inner packing element of box in use.
The broken lines represent environmental subject matter that forms no part of the claimed design.
